UNITED STATES PATENT OFFICE.

FRANK E. ECKHART, OF AUBURN, INDIANA.

DESIGN FOR A VEHICLE-BODY.

No. 38,776.

Specification for Design.

Patented Aug. 27, 1907.

Application filed April 12, 1907. Serial No. 367,899. Term of patent 7 years.

To all whom it may concern:

Be it known that I, FRANK E. ECKHART, a citizen of the United States, residing at Auburn, in the county of Dekalb, in the State of Indiana, have invented a new, original, and ornamental Design for Vehicle-Bodies, of which the following is a specification, reference being had to the accompanying drawings, which form part of this specification.

The figure of the drawing is a perspective

view of a vehicle-body showing my new design.

I claim:

The ornamental design for a vehicle body, as shown.

FRANK E. ECKHART.
